UNITED STATES PATENT OFFICE

116,819

DESIGN FOR A GYRO FLYER

Louis L. Driggs, Jr., Tipp City, Ohio

Application July 21, 1939, Serial No. 86,169

Term of patent 7 years

To all whom it may concern:

Be it known that I, Louis L. Driggs, Jr., a citizen of the United States, residing at Tipp City, in the county of Miami and State of Ohio, have invented a new, original, and ornamental Design for a Gyro Flyer, of which the following is a specification, reference being had to the accompanying drawing, forming a part thereof.

In the drawing:

Figure 1 is a perspective view showing my new design of a gyro flyer;

Figure 2 is a top plan view thereof;
Figure 3 is a bottom plan view thereof;
Figure 4 is a front elevation thereof;
Figure 5 is a rear elevation thereof; and
Figure 6 is as side elevation thereof.

I claim:

The ornamental design for a gyro flyer, substantially as shown.

LOUIS L. DRIGGS, JR.
